AKTIEBOLAGET NORDISKA ARMATURFABRIKerna, OF STOCKHOLM, SWEDEN, A
LIMITED COMPANY

BEATING OR HAMMERING TOOL

Application filed July 3, 1928, Serial No. 290,152, and in Sweden January 26, 1928.

The present invention relates to improvements in striking tools of the kind, which consists partly of a suitably power-rotated striking body, mounted to slide axially and

5 provided with one or more oblique striking faces, cooperating, in the striking position, with corresponding oblique faces located on an anvil and thus giving the striking body a recoil movement, and partly of an energy 10 storer, which cooperates with and is loaded by the striking body during the recoil movement of the latter for supplying the energy necessary for the striking movement.

The object of the invention is the provision 15 of a striking body consisting of or provided with one or more rollers, the circumferential faces of which form the oblique faces on the striking body.

Other characteristic features of the invention will be more clearly set forth in the following in connection with the embodiment 20 illustrated in the annexed drawing in which

Fig. 1 is a longitudinal section of the improved striking tool, and

25 Fig. 2 is a section on the line 2—2 of Fig. 1. Referring to the drawing in detail, 1 is the driving shaft. 2 is a guide-groove in said shaft of spiral or other shape. 3 is the striking body. 4 is a key, extending into the 30 guide-groove 2 and the striking body 3. 5 is a frame or support adapted to carry the anvil 6, 7 are the oblique faces formed as rollers mounted to turn at the front part of the striking body on studs 8 and screws 9 and constituting a part of said striking body. 10 are the oblique faces, arranged on the anvil 6 and 35 11 is an energy storer in the form of a spring, placed around the striking body 3.

The driving shaft 1 is rotated by means of 40 an electric motor 12, located in the frame 13, the rotor of which is fixed to the driving shaft 1, which is supported partly in a middle-bottom 14 in the frame 13 and partly in the handle 15 carried by the frame 13.

45 The arrangement works in the following manner.

Assuming that the parts occupy the position shown in the drawing: in this position the striking body 3—7 moves in a direction 50 towards the anvil 6 under the influence of the

spring 11, and is rapidly rotated by means of the motor 12, the rotating movement of which is transmitted to the striking body by the shaft 1 and key 4.

When the rollers 7 strike against the oblique 55 faces 10 of the anvil 6, the stroke will be transmitted to the anvil, and at the same time on account of the rapid rotation of the rollers over the oblique faces 10, the striking body 3—7 will be displaced axially against the influence of the spring 11, in which latter the energy necessary for the next successive striking movement of the striking body is stored. Although a spring has been disclosed herein 60 as the energy storing means it will be understood that any other convenient kind of energy storer may be used.

Having now particularly described the nature of my invention and the manner of its 65 operation, what I claim is:

1. In combination, a striking tool including 70 an anvil having oblique faces, a rotatable striking body mounted to slide axially and having an oblique striking face adapted, in the striking position, to cooperate with the oblique faces on the anvil to effect recoil movement, and an energy storer cooperating 75 with the striking body adapted to be rotated during the recoil of the striking body, the oblique face of the striking body including a roller disposed to engage the oblique face of the anvil.

2. In combination, a striking tool including 80 an anvil having oblique faces, a rotatable striking body mounted to slide axially and having oblique striking faces adapted, in the striking position, to cooperate with the oblique faces on the anvil to effect recoil movement, and an energy storer cooperating 85 with the striking body adapted to be rotated during the recoil of the striking body, the oblique faces of the striking body including rollers arranged on opposite sides of the axis of rotation of the striking body.

3. In combination, a striking body mounted 90 for rotary movement, an anvil having an oblique face, and a member rotatable on the striking body engageable with the oblique face of the anvil and mounted to rotate 100

about an axis substantially perpendicular to the axis of rotation of the striking body.

4. In combination, a striking body mounted for rotary movement, an anvil having an oblique face and members rotatable on the striking body engageable with the oblique face of the anvil and mounted to rotate about an axis substantially perpendicular to the axis of rotation of the striking body.

5. In combination, a striking body mounted for rotary movement, an anvil having an oblique face and members rotatable on the striking body engageable with the oblique face of the anvil and mounted to rotate about an axis substantially perpendicular to the axis of rotation of the striking body and located on opposite sides of the axis of rotation of said striking body.

6. In combination, a striking body mounted for combined rotary and axial movement, an anvil provided with an oblique face, a member rotatable on the striking body and engageable with the oblique face of the anvil, said member being rotatable about an axis substantially perpendicular to the axis of rotation of the striking body.

7. In combination, a striking body mounted for combined rotary and axial movement, an anvil provided with an oblique face, a member rotatable on the striking body and engageable with the oblique face of the anvil, and members rotatably mounted on the body and rotatable about an axis perpendicular to the axis of rotation of the striking body and on opposite sides of the latter.
